UNITED STATES PATENT OFFICE

161,621

AIRPLANE HELICOPTER TOY

Andrew Halvas, Astoria, N. Y.

Application January 22, 1949, Serial No. 389

Term of patent 7 years

(Cl. D34—15)

To all whom it may concern:

Be it known that I, Andrew Halvas, a citizen of the United States, residing in Astoria, State of New York, have invented a new, original, and ornamental Design for an Airplane Helicopter Toy, of which the following is a specification, reference being had to the accompanying drawing, forming part thereof:

Fig. 1 is a side elevation of an airplane helicopter toy, showing my new design;

Fig. 2 is a top plan view thereof;

Fig. 3 is a front elevational view.

I claim:

The ornamental design for an airplane helicopter toy, as shown.

ANDREW HALVAS.
